UNITED STATES PATENT OFFICE.

BENJAMIN O. HAUGH, OF ANDERSON, INDIANA.

DESIGN FOR A TILE.

SPECIFICATION forming part of Design No. 28,907, dated June 21, 1898.

Application filed November 1, 1897. Serial No. 657,118. Term of patent 14 years.

To all whom it may concern:

Be it known that I, BENJAMIN O. HAUGH, a citizen of the United States of America, residing in Anderson, in the county of Madison and State of Indiana, have invented and produced a new and original Design for Tiles, of which the following is a specification, reference being had to the accompanying drawings, forming a part thereof.

Figure 1 is a view of the face of the tile; and Fig. 2 is a sectional edge view of the same, taken through the line 2 2 and looking in the direction of the arrow. (See Fig. 1.)

My design relates to the surface ornamentation of a rectangular tile; and it consists of a series of disks D, arranged in parallel lines and at right angles to each other, so that the peripheries of adjacent disks shall be in contact and the peripheries of all the border or

outer disks shall be in line with the edges of the tile B. The design further includes a series of small disks, half-disks, and quarter-disks, as shown at d, the diameter of the small disks being such as to fit between and be in contact with the edges of the adjacent large disks. The quarter-disks are arranged at the corners of the tile, and the half-disks have their rounded edges in contact with two of the larger disks and their straight side on a line with the edge of the tile, as shown.

I claim—

The design for a tile herein shown and described.

BENJAMIN O. HAUGH.
